Primary Examiner — Rebekah A Caruso(57) **CLAIM**

The ornamental design for a mobile phone stand, as shown and described.

DESCRIPTION

FIG. 1 is a front elevational view of a mobile phone stand showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof; and,

FIG. 8 is a bottom, rear and left side perspective view showing the mobile phone stand in a use state.

The broken lines in the drawings illustrate portions of the mobile phone stand which form no part of the claimed design.
